UNITED STATES PATENT OFFICE.

WILLIAM H. ARMSTRONG, OF PLAINFIELD, NEW JERSEY, ASSIGNOR TO INGERSOLL-RAND COMPANY, OF JERSEY CITY, NEW JERSEY, A CORPORATION OF NEW JERSEY.

RIVET-SET RETAINER.

1,211,036.

Specification of Letters Patent.

Patented Jan. 2, 1917.

Application filed October 29, 1913. Serial No. 797,979.

To all whom it may concern:

Be it known that I, WILLIAM H. ARMSTRONG, a citizen of the United States, residing at Plainfield, in the county of Union 5 and State of New Jersey, have invented a certain new and useful Improvement in Rivet-Set Retainers, of which the following is a specification.

This invention relates to tool retainers 10 for percussive tools and more particularly to such a retainer for use in holding in the rivet set in a riveting hammer.

The object of the invention is to provide 15 such a retainer which will be of comparatively simple construction and yet capable of bearing the great stress which these retainers are often subjected to, for such a period of time that any chance of accident will be practically eliminated.

20 With this object in view, I have devised a rivet set retainer a practical embodiment of which is shown in the accompanying drawings in which:

Figure 1 shows an end elevation of the 25 tool and retainer with the head of the rivet set removed, Fig. 2 is a longitudinal section taken on the line II—II of Fig. 1, Fig. 3 is a transverse section taken on the line III—III of Fig. 2.

30 In Fig. 2 is shown the forward end of the barrel of the riveter 1, of ordinary construction, having a forward cylindrical portion 2 in which slides the shank 3 of a rivet set which comprises a head 4 and a neck 5, 35 a flange 6 being provided between the shank and the neck to limit the rearward movement of the rivet set and to furnish a holding surface for the rivet set retainer.

The retainer proper comprises a sleeve 7 40 having inturned flanges 8 and 9 at each end contacting with the cylindrical portion 2 of the tool barrel. This sleeve 7 is secured at its rear end to the tool barrel by any suitable means, being here shown as provided with 45 opposite slots 10 in the rear flange 9 which slide over lugs 11 on the outer surface of the barrel, the sleeve 7 being turned on the barrel slightly, after it has been slid into place so that the slots 10 do not register with the 50 lugs 11. Inside of the sleeve 7 is a spring 12 which is placed in the sleeve before it is slid

on to the tool barrel. Slidably mounted in slots 13 in the sleeve 7 are dogs 14 which are provided on their front ends with jaws 15 for grasping the rivet set and on their rear ends with inturned lugs 16 for engaging the rear end of the spring 12. To retain the dogs 14 in position a ring 17 is provided which surrounds the sleeve 7 and is secured thereon by rearwardly projecting lugs 18 60 which have grooves in their inner faces adapted to slide on to ridges 19 on the outer surface of the sleeve 7.

The operation of the device will be evident from the above description. If the tool 65 is started accidentally when the rivet set is not in contact with the work the impact of the flange 6 will be taken up by the dogs 14 which will be moved forward against the resistance of the spring 12, the force of the 70 piston blow being thus cushioned and the rivet set prevented from flying out of the cylinder.

Although the retainer is here shown in connection with a riveting tool, it is adapted 75 for use with any form of percussive tool or drill where the tool or drill is loosely held in the cylinder and it is to be understood that the present showing and description discloses only one specified modification of 80 my invention and other forms and modifications are included in the spirit and scope of the invention as expressed in the claim.

What I claim is:

In a tool retainer for percussive tools, a 85 tool cylinder, a sleeve surrounding the forward end of the tool cylinder and secured thereon against longitudinal movement, said sleeve having an inturned flange, a spring inside of said sleeve engaging said flange, a 90 dog mounted slidably in said sleeve, said dog having a tool grasping jaw and an inturned lug for engaging the rear end of said spring, and means for holding said dog in position. 95

In testimony whereof, I have hereunto set my hand.

WILLIAM H. ARMSTRONG.
